UNITED STATES PATENT OFFICE.

WILLIAM H. MARTYN, JR., OF MANCHESTER, NEW HAMPSHIRE.

CLOTHES POLE AND LINE HOLDER.

SPECIFICATION forming part of Letters Patent No. 289,290, dated November 27, 1883.

Application filed August 14, 1882. (No model.)

To all whom it may concern:

Be it known that I, WILLIAM H. MARTYN, Jr., of Manchester, in the county of Hillsborough, in the State of New Hampshire, have 5 invented certain new and useful Improvements in Combined Clothes Pole and Line Holder, of which the following is a specification.

My invention has for its object to make a 10 device that shall serve as a post or pole for supporting one end of the line, and in addition a bird-house or other ornamental feature, also serving for a housing or case for inclosing an apparatus for automatically drawing in the clothes-line when the same is not extended 15 and fastened. I attain these objects by the mechanism illustrated in the accompanying drawings, in which.

Figure 1 shows my invention partly in section and partly in elevation, and Fig. 2 shows the same, the plane of the view being at right angles to that of Fig. 1.

A represents the base, which may be made of wood or stone. This base A supports a hollow column, B B, which is surmounted by a bird-house, C, or any other ornamental structure. Within the hollow column B B, at or near its top, I suspend two or more sheaves (three being shown in the drawings) upon a 30 cross-rod, D.

W is a weight, also located within the column B B, and having at its upper end a number of sheaves, to correspond with the number at the top of the column.

35 R' R² R³ is a rope or line, fastened at one end at K, Fig. 1, and, after passing up and down, under, and over all of the sheaves E E' E² d d' d², it leaves the interior of the column B B at the pulley L, Fig. 2, as indicated by 40 R', Fig. 2.

The operation of my invention is as follows: The weight W and its sheaves E E' E², in its descent from the top, will draw in the line R' R² R³ R, as shown in the drawings. When 45 it is desirable to extend or draw out the line, the operator can, by pulling upon R', draw it out to its limit, this action causing the weight W to ascend to the top of the column. Any desired amount of line may be used in the column, as for each sheave added at the top and bottom two lengths of line can be provided for.

It will be seen that in my device I have provided means whereby the rope is kept constantly stretched and its parts kept separated and exposed to the air, so that there is no danger of its becoming moldy, and thereby marking the clothes. If taken in when wet, it is exposed to the action of the air, and soon dries. There are no springs to get out of order, and the rope is drawn in automatically by the descent of the weight.

I have shown a series of upper sheaves and a series of sheaves in the weight; but these are provided in order to avoid erecting a very high post. In the series of sheaves a long rope 65 can be wound around them, and a high post thus dispensed with. This device might be fixed to the side of a house under the eaves, or under a board or cover specially provided. Again, in cities, where the drying of the cloth- 70 ing is done on the house-tops, the upper sheaves can be fixed at the height at which the rope is to be stretched, and the weight permitted to fall down by the side of the house. In this last arrangement I dispense with the guide-sheave L and run the rope directly off one of the upper sheaves.

I am aware that it is not new in clothes-line holders to provide means for holding the line taut; also, that weights have been used for 80 such purpose, and that in some cases the weights have been connected to the rope by means of a pulley, and I do not broadly claim such as my invention; but

What I do claim, and desire to secure by 85 Letters Patent, is—

1. In a clothes-line holder, the combination, hereinbefore set forth, of an elevated support, a stationary sheave journaled upon the support, the clothes-line having one end made fast to a stationary staple or hitching device, and its other end left free and passed over and disposed in a depending fold below the stationary sheave, and thence outward over a suitable guide-pulley or bearing, and a take-up pulley placed in the depending fold of the clothes-line, and a weight supported upon the take-up pulley, all so arranged that the free end of the line may be drawn outward to any desired length and secured to a suitable fastening at a distance from the support, and when the said end is released will be drawn into a 90 95 100

taut depending fold below the stationary sheave, substantially as described.

2. In a clothes-line holder, substantially as described and shown, the combination of a vertically-disposed casing having a line-passage arranged a suitable distance above the ground, the shaft D, arranged within the upper end of the casing, a series of pulleys, *d*, secured on the said shaft, the weight W, arranged and operating within the casing, the shaft H, secured to said weight, the series of pulleys E, arranged on said shaft and corresponding to the series of pulleys *d*, the guide-

pulley L, journaled to the casing, with its periphery close to the line-passage, and the clothes-line having one end secured to a suitable support and its opposite end passed over guide-pulley L, through the clothes-line passage, and thence around the pulleys *d* E², in the manner shown and described, with its end made fast to the casing, all as and for the purposes set forth.

WILLIAM H. MARTYN, JR.
